UNITED STATES PATENT OFFICE

136,073

DESIGN FOR A COMBINED ENVELOPE MOISTENER AND SEALER

Douglas H. Freese, Portage des Sioux, Mo.

Application April 30, 1943, Serial No. 110,091

Term of patent 7 years

To all whom it may concern:

Be it known that I, Douglas H. Freese, a citizen of the United States, residing at Portage des Sioux, in the county of Saint Charles and State of Missouri, have invented a new, original, and ornamental Design for a Combined Envelope Moistener and Sealer, of which the following is a specification, reference being had to the accompanying drawing, forming part thereof.

Figure 1 is a front elevation of a combined envelope moistener and sealer, showing my new design.

Figure 2 is a side elevation thereof.

Figure 3 is a top plan view thereof.

I claim:

The ornamental design for a combined envelope moistener and sealer, as shown.

DOUGLAS H. FREESE.
